Harry C. Schmedes
ATTORNEYS.

UNITED STATES PATENT OFFICE.

WARREN M. WEBSTER, OF OAKLAND, CALIFORNIA.

WOOD TREATMENT.

Application filed November 28, 1924. Serial No. 752,742.

To all whom it may concern:

Be it known that WARREN M. WEBSTER, a citizen of the United States, residing at Oakland, in the county of Alameda and 5 State of California, has invented certain new and useful Improvements in Wood Treatment, of which the following is a specification.

My invention is an improved wood treatment to produce pictures thereon.

The object of my invention is to treat wood in such a way that a picture will be formed thereon, and which will have the appearance of being formed in the grain of 15 the wood—that is, it will not be pronounced.

In the annexed drawing, I have illustrated a block of wood with a picture formed in the grain thereof.

Referring more particularly to the drawing 20 my process is preferably carried out upon any grained material, preferably straight grain wood, and running in one direction only, although this is not absolutely essential.

25 The picture is formed on the block 1 by staining the foreground thereof in the grain of the wood with any small pointed instrument, such as a sable brush, as shown at 2. This foreground may be stained any desirable color to suit the requirements of the 30 picture. The high lines on the picture are left unstained, as shown at 3, thus bringing out the details of the picture.

The background at either side of the portion 35 2 is stained a lighter color, as shown at

4. Certain of the more defined grain lines, as shown at 5, are accentuated by staining in

a similar manner to give the appearance of depth, or carelessness thereto, so that the picture will not be entirely evident at first 40 glance. After this has been completed, the entire block 1 is covered with a colored varnish, thus retaining all of the stain in place preventing it from running and distorting 45 the picture.

Certain fine lines may also be carried over the picture in a careless manner to give a further natural appearance, as if the picture were actually formed in the grain of the 50 wood.

Having described my invention, I claim:

1. The process of treating wood to form 55 pictures thereon which consists in forming the picture of lines all of which run in the direction of the grain of the wood, and covering the picture with colored varnish.

2. The process of ornamenting wood which consists in forming a design on the surface 60 of the wood, said design being formed of parallel lines all of which run in the grain of the wood, and covering said surface with a colored varnish.

3. The process of ornamenting wood which 65 consists in placing a design on the surface of the wood, the foreground of said design being formed of colored lines, the background of said design being formed of lighter colored lines, all of said lines running in the direction of the grain of the wood, in accentuating the natural grain lines of the wood 70 and in covering said surface with a colored varnish.

In testimony whereof I affix my signature.

WARREN M. WEBSTER.
